ELEVATOR CONTROL SYSTEM

Frank E. Lewis, Forest Hills, Pa., assignor to
Westinghouse Electric & Manufacturing Com-
pany, a corporation of Pennsylvania

Application April 20, 1929, Serial No. 356,732

24 Claims. (Cl. 187—29)

My invention relates to control systems and has particular relation to control systems for elevator hoists and similar machinery.

An object of my invention is to provide a control system for a plurality of vehicles movable over a predetermined path, wherein the operation of each of the vehicles is automatic, requiring no attendants or operators to control the same.

Another object of my invention is to provide a control system for a bank of elevators in which the entire operation of the elevators is automatic, dispensing with the necessity for attendants to control the cars.

Another object of my invention is to provide a control system for a plurality of elevators in which the cars will be dispatched at regular intervals to make complete round trips and, when so dispatched, will automatically stop to take on and let off passengers in the same manner as though attendants on each of the cars were controlling the same.

Another object of my invention is to provide a control system for a plurality of elevators which shall include devices for permitting one of the cars to operate as an automatic push-button elevator, while the remainder of the cars are out of service, wherein two cars may be made to operate as interconnected push-button elevators to give service while the remainder of the cars are out of operation and wherein all of the cars may be operated as a bank of elevators dispatched at regular intervals to automatically perform all of the functions of elevator service without the necessity of attendants on the cars.

Another object of my invention is to provide an elevator system for use in a building having normal terminals and additional floors beyond the normal terminals wherein the car or cars will normally operate between the normal terminals but may, when service at additional floors is desired, move to such floors to give service thereat only when actual service is desired.

Modern elevator service requires that, in a bank of elevator cars, the cars shall be so distributed throughout the shafts or hatchways that, at no time, will two or more cars pass the same floors at approximately the same time, and such service also requires that the cars shall stop for passengers only when service is desired and only when the car making the stop is travelling in the direction indicated by the person or persons desiring to use the car. It is also desirable that, in any bank of elevators, one or more of the cars may be taken out of service when traffic condi-

tions warrant, leaving the remainder of the cars to answer the calls for service under such light traffic conditions.

The prior elevator systems, utilizing an attendant on each of the cars, could readily be made to answer all of the requirements for such service, but such elevators require, as an essential part of the system, the personal supervision of at least one person on each of the cars. I propose to construct an elevator system in which all of the functions, which have previously been performed by elevators having attendants thereon, shall be performed with an elevator system of the automatic type requiring no attendants.

My invention will be described with reference to the accompanying drawings wherein.

Figs. 1 and 2 jointly constitute a diagrammatic view of an elevator system including two elevator cars operating between the first and fourth floors of a building and operable, under certain conditions hereinafter specified, to a basement floor below the first floor of such building.

Referring to the drawings, I have illustrated two elevator cars C and C', each operable in its hatchway (not shown) past a basement floor, 1st, 2nd, 3rd and 4th floors in a building, the floors being designated by dotted lines marked with the legend, Basement, 1st floor, 2nd floor, 3rd floor and 4th floor.

Each of the elevator cars, C and C', is suitably driven by means of a variable-voltage drive, that for car C including a driving motor M illustrated as of the shunt-wound type, having its field winding MF and its armature MA connected, in parallel relation, to a suitable source of current supply indicated by line conductors L1 and L2. The armature MA of the drive motor M is directly coupled to an armature GA of a generator G, which armature is, in turn, connected in loop circuit with the armature EMA of a hoisting motor EM.

The generator G is provided with a separately-excited field winding GF and a cumulative series field winding GSF so proportioned as to produce substantially constant speed regulation for the hoisting motor EM, independent of variation in load upon the car C.

The hoisting motor EM has its separately-excited field winding EMF connected, for constant-voltage energization, to the source of power represented by line conductors L1 and L2. The hoisting motor EM has its armature EMA directly coupled to a hoisting drum D over which passes a cable Ca for supporting the elevator car C.

The driving equipment for elevator car C' is

identical, in all respects, with that just described for car C, and, in the following description, primed reference characters, corresponding to the reference characters applied to the elements for car C, will be used to indicate the elements of the driving and control system for car C'.

- At each of the 1st, 2nd and 3rd floors, I have illustrated a passenger-operated push-button for each direction of travel, those for the 1st floor being indicated by the reference character F1D to be used for calling any of the cars to take a passenger down from the first floor, and F1U to be used to call any of the cars to take a passenger up from the first floor. Push-buttons F2D, F2U, F3D and F3U perform a similar service for the 2nd and 3rd floors, respectively. A push-button FB at the basement floor is used to register a call for service for that floor, while a button F4 performs a similar service at the 4th floor.
- Buttons FB, F1D, etc., are connected, as hereinafter described, to control all of the cars in the bank to cause the cars to move to the corresponding floors to permit passengers to board the cars, while each of the cars is provided with a plurality of push-buttons mounted within the car, one button being provided for each floor served by the cars to be operated by passengers within the car to cause the same to be moved to the various floors at which passengers desire to leave the car. The buttons for car C are designated by the reference characters CB, C1, C2, C3 and C4, for the basement, 1st, 2nd, 3rd and 4th floors, respectively.

Each of the cars is provided with a floor selector FS suitably driven to duplicate, in miniature, the movements of the cars past the floors which they serve. Each of the floor selectors FS comprises a suitable base FSB, upon which are mounted a group of relatively short contact segments FCU connected, respectively, to each of the up-call buttons F1U, F2U, F3U and F4 mounted at the various floors. A second group of segments FCD are connected, respectively, to the down-call buttons FB, F1D, F2D and F3D mounted at the various floors. A third group of segments CCU is provided having its segments connected, respectively, to each of the car-call buttons CB, C1, C2, etc., carried by the car, while a fourth group CCD is, in like manner, also connected to the car-call buttons.

Each of the floor selectors is further provided with a plurality of normally-closed switches arranged in a group indicated by the reference character RU for the purpose of resetting or restoring the operated up floor-call buttons F1U, F2U, etc. When such call has been answered, while another group RD performs a similar service for the down-call buttons FB, F1D, etc.

Each of the floor selectors is provided with a movable arm A so arranged as to be moved across the floor selector base FSB in correspondence to the movements of the car C with which it is associated by means of a screw S suitably connected to some part of the driving equipment for elevator car C. The movable arm A comprises a lever extending to the right-hand side of the drawing, which carries a plurality of contact brushes 12 and 13 cooperating, respectively, with the groups of segments CCD and FCD as the car moves downwardly. The right-hand portion of the arm A also carries a device for momentarily opening each of the switches in group RD, this device being indicated as a wedge-shaped piece of insulating material 14 so aligned with the switches in group RD as to enter between, and

separate the contact members of such switches. A similar operating device 15 is arranged to engage and operate a throw-over switch 16 of the type commonly used in automatic push-button-elevator floor-selector systems.

Similar contact brushes 18 and 19 are mounted upon the left-hand side of the arm A to cooperate, respectively, with contact-segment groups CCU and FCU, while switch-operating devices 20 and 21 cooperate, respectively, with the group of normally-closed switches RU and with additional normally-closed switch 22 when the car is moving upwardly.

The selector arm A is suitably rocked about the screw S to cause the right-hand brushes and switch-operating devices to engage the cooperating segments and switches, when the car is moving downwardly, by means of a throw-over magnet DS, or the arm A is rocked in the other direction, when the car is moving upwardly, by means of a throw-over magnet US. The selector described in the foregoing description is similar to the selectors now in general use for operating elevator signal systems and push-button control systems, and I believe needs no further description.

The direction of movement of the elevator car C is suitably determined by the operation of an up-direction switch 1 and a down-direction switch 2 operable to reverse the direction of the current supplied to the generator field winding GF, which, in turn, determines the direction of current supplied to the armature EMA of the hoisting motor EM.

The direction switches 1 and 2 are suitably controlled by an up-direction-determining relay UD and a down-direction-determining relay DD.

In order that, when a car is started in either direction, it shall continue to travel in that direction as each stop is made to take on or let off passengers, a through-trip relay 6 and a restart relay 7 are provided. The through-trip relay insures that the car will move to that terminal in the direction in which the car starts its initial movement, while restart relay 7 operates the car to restart after each stop is made to take on or let off passengers.

A transfer relay 8 is utilized for transferring the control of the car from the starting circuits to the stopping circuits, hereinafter described, as soon as the car gets under way after each successive stop, while a floor-call stopping relay 9 operates, as hereinafter described, to cause the car to stop in answer to calls registered by call-buttons FB, F1D, etc. at the floors, and a car-call stopping relay 10 is utilized to stop the car in response to call-buttons CB, C1, C2, etc. operated from within the car.

A suitable dispatching device indicated by the legend, "Dispatcher", is utilized to time the departure of each of the cars from its lower and from its upper terminal. The "dispatcher" illustrated is represented by a constant-speed motor DM driving a plurality of dispatching discs 23, 23', 24, and 24' to start the cars, as hereinafter described. A switch DM is provided to connect the dispatching motor DM to the source of power.

Each of the cars is provided with a suitable collapsible gate, that, for car C, is represented by the reference character GS, while each of the hatchways in which the cars move, is provided with a suitable hatchway door for each of the floors served by that car. The doors associated with car C are indicated by the reference characters DB, D1, D2, D3 and D4 located at each

of the basement, 1st, 2nd, 3rd and 4th floors, respectively.

Each of the cars is further provided with a load switch LS which opens one set of contact members and closes another set when the load upon the car reaches a predetermined value.

Since my elevator system is designed to operate with one car only in service, with two cars only in service or with a greater number of cars in service, I have provided a plurality of switching devices which may be manipulated to cause the cars to operate as a single-car or as a two-car or as a multi-car system, when any one of these systems is desired. These switches are arranged to change the method of dispatching the cars in accordance with the type of system desired at any given time. Switches 25 and 26 are arranged to be operated when it is desired to operate car C alone, while switches 25' and 26' are arranged to be operated when it is desired to use the car C' alone. Switches 27 and 27' are arranged to be operated when it is desired to operate cars C and C' jointly, as a two-car system.

My system will be best understood with reference to a series of operations; first, that of car C operating as a single car; second, that of cars C and C' operating as a two-car system; and third, that of cars C, C' and others (not illustrated) as a multi-car system.

Assuming that elevator car C is to be operated as a single-car system, it will be presumed that switch 25 is open, while switch 26 is closed. The "dispatcher" may be stopped, since there is no point in dispatching a single car except when a call for service is desired.

Assuming that car C is at the first floor, the floor selector arm A will have operated and opened switch 16, while switch 22 will be in closed-circuit position. The closed condition of switch 22 will cause up-direction-determining relay UD to be energized by way of a circuit which extends from line conductor L1, through conductors 30 and 31, contact members b on a basement call relay BC, conductor 32, the normally-closed contact members of switch 22 on floor selector FS, conductor 33, the coil of up-direction-determining relay UD, conductor 34, normally-closed contact members a on down-direction-determining relay DD, conductors 35 and 36, switch 26 and conductor 37, to line conductor L2.

Up-direction-determining relay UD, when energized, completes a self-holding circuit which extends from line conductor L1 to the coil of relay UD, as previously described, and thence, by way of conductor 34, contact members a on relay DD, conductors 35 and 38, contact members b on relay UD and conductors 39 and 40, to line conductor L2. The car will be in a condition to start upwardly in response to the operation of any of the call-buttons F2U, F2D, etc. or buttons C2, C3, etc.

Assuming that a person at the 2nd floor, desiring to travel upwardly, operates button F2U. Since the car C was stopped, a circuit for energizing a dispatching relay DR is completed. This circuit extends from line conductor L1, through conductor 41, the normally-closed contact members a of each of the push-buttons F4, F3U, F3D, F2U, F2D, F1U, F1D and FB in series relation with conductor 42, normally-closed contact members a on up-direction switch 1 for car C, conductor 43, normally-closed contact members a on down-direction switch 2 for car C, conductor 44, normally-closed contact members a on up-direction switch 1' for car C', conductor 45, normally-closed contact members a on down-direction

switch 2' for car C', conductor 46 and thence, in series relation, through normally-closed contact members on both the up and down-direction switches for each of the cars in the bank of elevators to which my system will be applied, thence, by way of conductor 46, the coil of dispatching relay DR and conductors 47 and 48, to line conductor L2. Hence, the operation of button F2U will open contact members a on this button and will open the circuit just described for dispatching relay DR. Relay DR, being deenergized, will close its contact members d to complete a circuit for up-direction switch 1 for car C. This circuit extends from line conductor L1 through conductors 30 and 49, whence it extends in series relation through suitable door interlocking switches 50, 51, 52, 53 and 54 associated, respectively, with each of the doors D4, D3, D2, D1 and DB in the hatchway for car C, thence, by way of conductor 55, gate switch 56, conductors 57 and 58, the coil of up-direction switch 1, conductor 59, contact members c on up-direction-determining relay UD (now closed), conductors 60 and 61, normally-closed contact members b of transfer relay 8, conductors 62 and 63, contact members d on dispatching relay DR and conductor 48, to line conductor L2.

Up-direction switch 1, when energized, supplies current to the field winding GF of generator G to start the car upwardly by way of contact members b and c on up-direction switch 1, while contact members d on up-direction switch 1 will complete a self-holding circuit for this switch which extends from line conductor L1, to the coil of up-direction switch 1, as previously described, and thence, by way of conductors 59 and 64, contact members d on up-direction switch 1, conductors 65 and 66, contact members b of floor-call stopping relay 9, conductor 67, contact members b of car-call stopping relay 10 and conductor 68, to line conductor L2.

The car starts upwardly and, as the voltage output of the generator G reaches a predetermined value, transfer relay 8 will be energized to open the initial energizing circuit for up-direction switch 1, leaving this switch energized by way of its holding circuit, thus placing the operation of the car now under control of floor-call stopping relay 9 or car-call stopping relay 10. The circuit for transfer relay 8 extends from loop circuit conductor 69, by way of conductor 70, the coil of transfer relay 8, and conductor 71, to the opposite loop-circuit conductor 72.

The car will continue upwardly until it approaches the 2nd floor, at which time, the floor-selector arm A will have moved into a position just below the dotted line indicated by the legend, 2nd, on floor selector FS, thereby bringing contact brush 19 on the arm A into engagement with segment 73 in the group of contact segments FCU. At this time, a circuit will be completed for energizing floor-call stopping relay 9, which extends from line conductor L1, through conductor 74, contact members b on floor button F2U, conductors 75 and 76, contact segment 73, contact brush 19 on floor selector FS, conductor 77, the coil of car-call stopping relay 9, conductors 78 and 79, bypass button P on car C and conductors 80 normally closed contact members 81 on load switch LS and conductor 82, to line conductor L2.

It will be observed, by an inspection of the floor-call buttons FB, F1D, F1U, etc., that each of these buttons is provided with a suitable magnet normally energized, except when a car arrives level with the corresponding floor, for the purpose of

140

145

150

maintaining these push-buttons in actuated position when operated. The magnet F2U' for button F2U is connected in a circuit which extends from line conductor L1, through conductor 83, the magnet coil F2U', conductor 84, normally-closed switch 85, constituting one of the group of switches RU on floor selector FS, conductor 86, normally-closed contact switch 85', constituting a part of the group of switches RU' on floor selector FS', conductor 87 and thence, in series relation, through each of the corresponding switches constituting portions of the RU group of switches on each of the selectors for each of the additional elevators in the bank and thence, by way of conductor 88, to line conductor L2.

Car-call stopping relay 9, when energized, opens its contact members b to break the holding circuit for up-direction switch 1, and the car will be brought to a stop at the 2nd floor level by means of a brake or any suitable landing or levelling mechanism commonly used to stop elevators, which apparatus it is not deemed necessary to more elaborately illustrate or describe.

As the car stops at the 2nd floor, the floor selector arm A will have moved into alignment with the dotted line on floor selector FS indicated by the legend, 2nd, and the switch-operating device 20 will have moved between, and separated the contact members of, switch 85, thereby opening the circuit for the holding magnet F2U' for button F2U, resetting or restoring this button to its normal unoperated condition.

It will be observed that transfer relay 8, which will be deenergized when the car is brought to a stop, is provided with a dashpot or other retarding device 89, preventing this relay from closing its contact members for a predetermined time after the car is brought to a halt. The time delay provided thereby allows sufficient time for the prospective passenger at the 2nd floor to open the door D2 at that floor, and the car gate GS before relay 8 will complete the circuit for restarting the car. It will be observed that the car cannot restart with the doors and gates open since the circuit for the direction switches extends through the door and gate switches, hence, the passenger now on the car must reclose both the door D2 and the gate GS.

The passenger may then operate one of the car buttons CB, C1, etc., dependent upon the floor to which he desires to travel. Assuming that the passenger desires to travel to the 3rd floor and operates button C3, the car will be started upwardly to take him to the 3rd floor.

It will be observed that the fact that the car started upwardly to answer the 2nd floor call, has, by such initial movement, energized through-trip relay 6. The initial closing of the up-direction switch completes a circuit for energizing through-trip relay 6 which extends from line conductor L1, through conductors 90, 91, contact members e on up-direction switch 1, conductors 92 and 93, the coil of through-trip relay 6, conductors 94 and 95, contact members e on up-direction-determining relay UD and conductors 96 and 49, to line conductor L2. Through-trip relay 6, when energized, completes a self-holding circuit for itself which extends from line conductor L1, through conductors 97 and 98 and 99, contact members c on through-trip relay 6, to the coil of through-trip relay 6, and thence, by way of conductor 94, to line conductor L2, as previously traced for this coil.

Hence, independent of whether the passenger on the car operates a button CB, C1, C2, etc., the

car will again start upwardly as soon as the doors and gates are closed, since through-trip relay 6 opens the circuit for restarting relay 7, permitting this relay to maintain its contact members closed until the car has reached the upper terminal. It will be observed that, with restart relay 7 deenergized, thus closing its contact members, the circuit for energizing the up-direction switch extends from line conductor L1, through the door and gate contacts by way of conductors 57 and 58 (previously traced for up-direction switch 1) and thence to the coil of up-direction switch 1 and thence, as previously traced, by way of conductors 59 and 62 whence, instead of extending to relay DR, the circuit now extends, through conductor 100, contact members of restart relay 7 and conductor 101, to line conductor L2.

However, it is assumed that the passenger boarding the car at the 2nd floor, desires to leave the car at the 3rd floor and, therefore, operates button C3 to close contact members b on this button, which will be maintained closed by means of holding magnet 102 similar, in all respects, to the holding magnets for the floor buttons previously described.

As the car approaches the 3rd floor, movable arm A on floor selector FS will move contact brush 13 into engagement with contact segment 103 (constituting one of the group of segments 105 CCU) and a circuit will be completed for operating car-call stopping relay 10, which extends from line conductor L1, through conductors 97, 98 and 104, contact members b of button C3, conductor 105, contact segment 103, contact brush 110 13 on floor selector FS, conductor 106, the coil of car-call stopping relay 10 and conductor 68, to line conductor L2.

Car-call stopping relay, when energized, opens the holding circuit for the up-direction switch 115 1 in the same manner as did the operation of floor-call stopping relay 9, and the car will be brought to rest at the 3rd floor.

However, it will be apparent that, upon the exit of the passenger at the 3rd floor, through-trip relay 6, remaining energized, will cause the car to restart and move to the 4th floor, thus completing an up trip for this car.

It will be apparent that if, during the time intervening between the starting of car C from the 1st floor to the time it arrives at the 4th floor, other calls had been registered by actuation of either up floor buttons F2U or F3U, these buttons would have supplied current from line conductor L1 to the respective contact segments in group FCU to thereby cause energization of hall-call stopping relay 9 to cause the car to stop at the respective floors as it approaches them. While I have shown but four floors in my illustrated system, it will be apparent that my system may be adapted for as many floors as is desired by supplying additional segments and normally-closed switches upon the floor selector FS.

When the car arrives at the uppermost floor 140 or top terminal, switch-operating device 21 on floor-selector arm A will open switch 22, thereby breaking the circuit which has, up to this time, maintained up-direction-determining relay UD in actuated condition, thus permitting this relay 145 to close its contact members a to thereby energize down-direction-determining relay DD. It will also be apparent that, when the car started from the 1st floor, throw-over switch 16 on floor selector FS will have been moved to closed posi- 150

tion, hence, a circuit may now be traced for down-direction-determining relay DD, which circuit extends from line conductor L1, through conductors 30 and 107, throw-over switch 16, conductor 108, the coil of down-direction-determining relay DD, conductor 109, contact members *a* on up-direction-determining relay UD (now closed), conductors 110, 111 and 112, switch 26 and conductor 37, to line conductor L2. The operation of relay DD prepares the car to travel downwardly in answer to calls for service in the down direction.

During the interval of changing from the up-direction control to the down-direction control by the transfer of control from relays UD and DD, there will be a period during which the circuit for through-trip relay 6 will be open at contact members *e* on relay UD and also during this period, the holding coils for the car-buttons CB, C1, etc. will be opened by contact members *e* on relay UD. It will be observed that, with up-direction-determining relay UD or down-direction-determining relay DD closed, a circuit from line conductor L1, through conductors 97 and 98, will be completed for the holding coils for buttons CB, C1, etc. in series relation, which extends thence by way of conductor 113 and either by way of conductor 95 and contact members *e* on up-direction-determining relay UD, or by way of conductor 114 and contact members *e* on down-direction-determining relay DD.

With no calls for service, (that is, no floor-call buttons F4, F3U, etc. in operated condition) and the car stopped at the top floor, relay DR will have its coil energized to prevent restarting of the car, and, with no buttons CB, C1, etc. operated, restarting relay 7 will have its coil energized to prevent restarting of the car and hence, the car will remain at the uppermost floor until a button at another floor or a button in the car is actuated. The operation of a button at one of the floors causes the car to start in the down direction in the same manner as was described for the original starting of the car. However, assuming that someone at the 4th floor boards the car and operates one of the push-buttons CB, C1, etc., the opening of contact members *a* on any of the car-call buttons CB, C1, etc. will cause de-energization of restarting relay 7 by opening the normal circuit for this relay, which extends from line conductor L1, through conductors 97 and 115, contact members *a* on each of the car buttons in series relation, conductor 116, the coil of restarting relay 7, conductor 117, contact members *b* on through-trip relay 6 (now deenergized as previously explained), and conductor 101, to line conductor L2.

However, as soon as relay 7 is deenergized to close its contact members, a circuit will be completed for the down-direction switch 2 which extends from line conductor L1, through conductors 30 and 49, door switches 50, 51, 52, 53 and 54, conductor 55, gate switch 56, conductors 57 and 118, the coil of down-direction switch 2, conductor 119, contact members *c* on down-direction-determining relay DD, and conductors 120 and 61, contact members *b* of transfer relay 8, conductors 62, 63 and 100, the contact members of restarting relay 7 and conductor 101, to line conductor L2.

The car will start downwardly, stopping in response to any actuated call-button or car-button, in the manner described with reference to stops in the up direction except that the floor selector arm A will now be in a position to en-

gage contact brushes 12 and 13 with segment groups CCD and FCD, respectively, since the car is travelling downwardly.

The transposition of the floor-selector arm A from engagement with its "up" groups of segments to engagement with its "down" groups of segments, occurs when the up-direction-determining relay UD drops out and the down-direction-determining relay is picked up. It will be observed that the circuit for magnet DS, which causes the selector arm A to rock to what may be termed the "down position", extends from line conductor L1, through conductors 30, 121 and 122, contact members *d* on down-direction-determining relay DD, conductor 123, the coil of down selector magnet DS, conductors 124, 125 and 79, bypass switch P, conductor 80, contact members 81 on load switch LS, and conductor 82 to line conductor L2. Hence, until relay DD drops out when the car arrives at the lowermost terminal, selector arm A will be in such position that it can engage only the down segments CCD, FCD and switches RD.

Since the car, once started downwardly, will continue to travel downwardly by virtue of energization of through-trip relay 6, restarting after each stop, it is desirable, in some instances, that the car should be stopped prior to the time of reaching the basement. In other words, it may be desirable that the first floor should be the normal terminal for this car. Hence, I have located switch 16, which normally reverses the direction-determining relays UD and DD at the end of a down trip, to be actuated when the car arrives at the 1st floor rather than at the basement floor. But it will be observed that the segment 126 in group FCD on the floor selector will be continuously supplied with current from line conductor L2 through contact members *b* on basement button FB so as to cause energization of floor-call stopping relay 9 each time the car approaches the 1st floor. Hence, the car will stop at the 1st floor on each down trip unless a call exists for service at the basement floor.

Assuming that no call exists at the basement floor, the car will be stopped, since a circuit extending from line conductor L1, by way of conductors 127 and 128, normally-closed contact members *b* on floor button FB at the basement floor, conductors 129, 130 and 131, segment 126, brush 13, conductors 132 and 77, the coil of floor-call stopping relay 9, conductors 78 and 79 bypass button P and conductor 80, contact members 81 on load switch LS, and conductor 82, to line conductor L2 will be completed to operate car-stopping relay 9.

As the car arrives at the 1st floor, switch 16 will be opened to thereby drop out down-direction determining relay DD and to permit up-direction-determining relay UD to be energized to prepare the car for another upward trip.

Assuming, however, that someone at the basement, desiring to use the car, operates button FB, the circuit for supplying current to segment 126 will be broken at contact members *b* on button FB while a circuit will be completed to segment 133 to stop the car at the basement floor and, also, a branch of that circuit will be completed through coil 134 on basement call relay BC. This circuit extends from line conductor L1, through conductor 135, contact members *c* on basement call relay FB and conductor 136, to junction point 137, one branch of the circuit extending by way of conductor 138, to segment 133, while another branch of the circuit extends, by way of con-

ductors 139 and 140, to the coil 134 of basement call relay BC and by conductors 141 and 48, to line conductor L2.

Basement call relay BC, when energized, prevents closing of the circuit for up-direction-determining relay UD by opening its contact members *b*, while the closing of its contact members *a* shunts switch 16 by way of conductors 31 and 142 to prevent opening or dropping out of down-direction-determining relay DD as the car approaches or passes the 1st floor. Hence, the car will continue downwardly to the basement floor, stopping thereat in the same manner as described for other stops.

When the car arrives at the basement floor, switch-operating device 14 on selector arm A will engage and open switch 143 to restore the floor-button FB to normal condition, thereby deenergizing basement call relay BC, permitting this

relay to open the shunt around switch 16 (now in open-circuit position) and permitting the closing of the circuit for up-direction-determining relay UD to prepare the car for an upward trip. In like manner, the actuation of car-button CB will cause the car to move to the basement floor, since operation of this button energizes a second coil 144 on basement call relay BC, in the same manner as previously described for the operation of coil 134 by floor-button FB.

It will, therefore, be apparent that the car will operate between the 1st and 4th floors at all times except when a call exists for service at the basement floor, at which time, the car will be prevented from reversing at the 1st floor but will be carried to the basement in answer to that call.

It will be observed from the foregoing description that the car C may be operated as a single car which will operate in response to calls for service, collecting all of the passengers who desire to travel in the up direction during the upward trip and collecting all of the passengers desiring to travel downwardly during the downward trip.

A further condition of operation will be satisfied by my system, namely, that of having the car standing at the lower terminal or 1st floor when a call for service is registered at the basement floor. The operation of the basement button FB or CB operating relay BC will cause the car to respond to that call.

It will be observed that, when the car is standing at the 1st floor, switch 16 having been opened, relay UD will be closed to prepare the car for an upward trip, while the floor-selector arm A will have been shifted to the up position, so that the call for service at the basement floor must reverse these connections in order that the car may start downwardly. By extending the circuit for the up-direction relay UD through contact members *b* on relay BC and by shunting switch 16 by contact members *a* on relay BC, the previously set condition of the direction-determining relays will be reversed, and the car may start downwardly to respond to the call.

It will be observed that car C' may be operated alone as a single car system by closing switch 26' and opening switch 25', whereupon car C' will operate in precisely the manner previously described for car C.

Assuming that it is desired to operate two cars as a two-car system, switches 26 and 26' will be opened, switches 25 and 25' will be opened and switches 27 and 27' will be closed.

In this event, one of the cars will be "parked" or have its normal station at one of the terminals, while the other car will have its normal station

at the opposite terminal, and, as one car moves upwardly, the other car will be automatically started downwardly to reverse the positions of the car.

Assuming that car C is at the lowermost terminal and car C' at the uppermost terminal, car C will have its up-direction-determining relay UD energized, while car C' will have its down-direction-determining relay DD' energized. Assuming that car C was the first car to reach its terminal and opened switch 16, relay DD will be de-energized to prepare a circuit for actuating relay UD in the manner described with reference to the one-car operation. However, the circuit for UD cannot be completed until car C' arrives at its upper terminal, since now the energizing circuit for relay UD extends through normally-closed contact members *f* on up-direction-determining relay UD' for car C'.

This circuit extends from line conductor L1, through conductors 30 and 31, contact members *b* on basement call relay BC, conductor 32, switch 22 on floor selector FS, conductor 33, the coil of up-direction-determining relay UD, conductor 34, contact members *a* on down-direction-determining relay DD, conductors 35 and 36, switch 27, conductor 151, contact members *f* on up-direction-determining relay UD' and conductors 152 and 40', to line conductor L2. Hence, the up-direction-determining relay for car C cannot be energized until car C' arrives at its upper terminal and drops out its up-direction-determining relay. However, as soon as the car C' arrives at its upper terminal, up-direction-determining relay UD will be energized.

At the same time, down-direction-determining relay DD for car C, having been deenergized, will complete a circuit for energizing direction-determining relay DD' for car C' by way of a circuit which extends from line conductor L1, through conductors 153 and 154, switch 16' on floor selector FS', conductor 155, the coil of down-direction-determining relay DD', conductor 156, contact members *a* on up-direction-determining relay UD', conductor 157, switch 27, conductor 158, normally-closed contact members *f* on down-direction-determining relay DD for car C and conductors 159 and 40, to line conductor L2. Both cars are now in condition to start trips—car C to start an up trip and car C' to start a down trip.

However, neither car may start until a call is registered, by virtue of the fact that both cars are under the control of dispatching relay DR, the coil of which will be energized since all of the floor buttons FB to F4 have their contact members *a* closed and both cars will have their direction switches 1 and 2, and 1' and 2', deenergized, also, no car-buttons in either car having been operated, relay 7 for car C and relay 7' for car C' will be energized, thus preventing starting of the car through the contact members of these relays.

Assuming now that a person at the 2nd floor, desiring to travel upwardly, operates the button F2U, the cars will be started. Car C will be started because relay DR will be deenergized, which operation has been previously described with reference to the single-car operation. Car C' will also be started, since the circuit for its direction switches will be closed through contact members *a* on dispatching relay DR, which circuit extends from line conductor L1, through conductors 153 and 160, door switches associated with doors D4', D3', D2', D1' and DB' associated

with car C', conductor 161, gate switch GS', conductors 162 and 163, the coil of down-direction switch 2', conductor 164, contact members *a* on down-direction-determining relay DD', conductor 165, contact members *b* of transfer relay 8', conductors 166 and 167, contact members *a* on dispatching relay DR and conductors 47 and 48, to line conductor L2. Through-trip relay 6 for car C will be energized as described for the 10 single-car operation, while through-trip relay 6' for car C' will also be energized by way of a similar circuit, hence, car C will be started upwardly and car C' will be started downwardly.

Car C will stop at the 2nd floor to take on 15 the passenger, in the manner previously described with reference to a single-car operation, while car C' will continue downwardly, answering all "down" calls for service until it reaches the 1st floor, whereupon it will open switch 16' 20 to drop out direction-determining relay DD' and will thereafter wait at the lower terminal until car C has arrived at the upper terminal, since up-direction-determining relay UD' cannot be energized to prepare car C' for upward trip until 25 up-direction-determining relay UD for car C has been deenergized upon the arrival of that car at its upper terminal.

The purpose of so interlocking the direction-determining relays for cars C and C' is that, if 30 one car should arrive at its terminal before the other car has answered all the calls in the direction in which it is travelling, the car reaching the terminal would immediately reverse and, as soon as it started, would open the contact members *a* on its direction switch to deenergize relay DR, having the effect of indicating that a call 35 for service existed even after the opposite car had answered all the then existing calls. In other words, the cars would be forced to continuously travel upwardly and downwardly until, perhaps by accident, one reached its terminal at just the same time that the other car reached its terminal, before either of the cars would stop, even though no calls had existed for service during 40 several trips. However, by such interlocking as that previously described, one car is forced to wait at its terminal until the opposite car has arrived at its terminal, and then, if no calls for service exist, these cars will remain stationary 45 until another call is registered, whereupon both cars will again start, as previously described, each to make a through trip to answer such calls.

It will be apparent that the floor-basement-call button FB or the car-basement-call buttons CB 55 and CB' will be effective to cause the cars to move to the basement whenever such service is desired, since the circuit for basement call relay BC has a parallel branch extending from conductor 129, by way of conductor 168, to the coil 169 of a basement call relay BC' and thence, by way of conductor 170, to line conductor L2, so that this relay will operate to apply the basement call to car C' as well as to car C. In addition, basement call relay BC' has an additional coil 171 in 60 circuit with car-button CB' so that this car may be sent to the basement to permit passengers on car C' to leave the car at the basement floor.

By providing relays BC and BC', each with 70 an additional operating coil connected, respectively, to the car-buttons, individual to the associated cars, that car upon which a passenger, wishing to go to the basement, is riding may, alone, be sent to the basement without necessitating the operation of the other car to the base-

ment but permitting this car to continue its normal operation.

It will, therefore, be apparent that my system may be utilized with two cars only, operating as a two-car system in which one car will move upwardly, while the other is moving downwardly, each giving service wherever such service is desired. 80

Assuming now that it is desired to use my system, with additional cars, as a multi-car elevator system, switches 27, 27', 26, 26' will be opened, while switches 25 and 25' will be closed and the dispatcher, indicated by the legend "Dispatcher", will be started to time the departure of several cars from their lower terminal or from their upper terminal, the switch DMs being provided for this purpose. 85

I have illustrated the dispatcher as comprising contact segments 23 and 23', 24 and 24', for dispatching two cars though it is to be understood that, to adapt this dispatcher for a greater number of cars, additional contact segments or discs must be added for each additional car. It is to be understood that the relative position of each of the discs 23, 23', etc. is adjustable to properly 100 adjust the time intervals for up and down trips to suit the traffic conditions existent at any portion of the day, and also to change the intervals between the dispatching of any two of the cars if such adjustment is desired. By varying a resistor R associated with the field winding of a motor DM, it will be understood that the time interval between all of the cars may be lengthened or shortened. 95

Assuming that all of the cars are at the 1st 110 floor, down-direction-determining relays DD, DD' and those associated with additional cars will be deenergized, since each of the cars will have its switch 16 or 16', etc., on the associated floor selectors in open-circuit condition. Hence, 115 circuits are prepared for energizing up-direction-determining relays UD, UD' and others associated with additional cars. However, these circuits cannot be completed, since the connection between each of the coils of these relays and line 120 conductor L2 is opened at the dispatching segments until the dispatcher is rotated to bring the associated segments into engagement with its brush or other suitable contacting devices.

Assuming that segment 23 is brought into a 125 position to engage the contact member 180, a circuit will be completed for the up-direction-determining relay UD for car C which extends from line conductor L1, through conductors 30 and 31, contact members *b* on basement call relay 130 BC, conductor 32, switch 22 on floor selector FS, conductor 33, coil of up-direction-determining relay UD, conductor 34, contact members *a* on down-direction-determining relay DD, conductors 35, 36 and 181, contact members 80 and 23 135 of the dispatcher and conductors 182 and 32, to line conductor L2.

Up-direction-determining relay UD will, therefore, be energized to prepare the car C to travel upwardly. In this case, however, switch 25 is in 140 closed-circuit position and hence, it is not necessary that a call shall exist in order to get the car C to start but this car will be automatically started by the dispatcher to start upwardly and to make a complete upward trip. The closing of 145 contact members *c* on up-direction-determining relay UD completes a circuit for the up-direction switch 1 which extends, as previously traced for this coil, to conductor 62 and thence, by way of switch 25 and conductor 183, to line conductor 150

5 L2. Expressed in another way, switch 25 acts to permanently register a call for starting the car as soon as the dispatcher gives the impulse indicating that it is time for this car to start a trip.

10 The car C, when started, continues to travel upwardly to answer all calls, as was described with reference to both the single-car operation and to the two-car operation, since through-trip relay 6 will have been energized as previously described.

15 When car C arrives at the upper terminal, it will open its contact switch 22 to drop out the up-direction-determining relay UD, but the down-direction-determining relay DD will not immediately pick up, since the only way in which the circuit for this relay may now be completed is through dispatcher segment 24. When dispatcher segment 24 is moved into engagement with its 20 cooperating brush, down-direction-determining relay DD will be energized and, since switch 25 is closed, placing a permanent call upon car C, the car will immediately start downwardly to complete a down trip. When the car C arrives 25 at the lower terminal, down-direction-determining relay DD drops out upon the opening of switch 16 on floor selector FS, and the car stands at the lower terminal floor until the dispatcher segment 23 again engages brush 180 to start this car on 30 its next up trip.

35 In like manner, dispatcher segments 23' and 24' will cause the starting of car C' in the up direction and in the down direction, respectively, when these segments are brought into engagement with their cooperating brushes.

40 It will be observed that the floor-call buttons FB, F1D, F1U, etc. have their circuits extending to the FCU and FCD groups of segments on floor selector FS paralleled to corresponding segments in groups FCU' and FCD' on car C, so that the calls registered on the floor-call buttons will be common to all cars in the bank, whereas, the car-call buttons CB, C1, etc. on car C, and buttons CB', C1', etc. on car C' are individually connected 45 to the CCU and CCD groups of segments on the selector associated with the respective car only, hence, calls set up by the car call buttons will be answered only by the associated car.

50 It will be observed that each of the cars C and C' is provided with a load switch, that for car C being indicated by the reference character LS, which will operate to automatically dispatch car C from the lower terminal when the car is fully loaded. For example, assuming that car C is 55 standing at the lower terminal and sufficient persons enter the car at that floor to load the car to its capacity, the weight of the passengers on the car will overbalance the pressure exerted by spring LSS, allowing the lever of the car switch to rotate about its pivot LSP to open contact members 81, breaking the circuit for floor-call stopping relay 9 in the same manner as though bypass switch P had been operated, since, if the car is loaded, there will be no point in permitting 60 this car to stop in response to calls for service from the various floors. Load switch LS will, in addition, close its contact members 185 to place a shunt around the dispatcher segment 23 to automatically dispatch this car without waiting 65 for the dispatch impulse to be given by the dispatcher. The car will then travel upwardly, stopping in answer to calls registered on car buttons C1, C2, etc., but will not stop in answer to floor-call buttons F1, F2, etc., until the load on car C 70 is reduced by passengers leaving the car, per-

mitting load switch LS to reclose its contact members 81.

75 Each of the other cars in the bank will, in like manner, be provided with a load switch to perform a similar service for those cars.

80 In the manner described with reference to the single-car operation and the two-car operation, all of the cars in the bank will operate normally to the 1st floor as a lower terminal, but each of the cars is adapted to move to the basement floor whenever a basement call exists, since each of the cars is provided with a basement call relay BC to perform functions for that car similar to those described with reference to car C.

85 The feature of providing the lower floor as a lower terminal and permitting the car to go to the basement when service is desired renders it necessary that a departure shall be made from the usual method of operating the floor lanterns which indicate the direction in which the car is to travel whenever it makes a stop at any of the floors.

90 I have indicated a plurality of floor lanterns, one set for each of the cars in the bank, comprising an "up" lantern and a "down" lantern at each of the floors served by the cars except 100 the upper terminal floor and the basement floor which are provided with a single lantern only to indicate the approach of a car to the terminal floors.

95 The lanterns associated with car C are designated by the reference characters LB, L1D, L1U, L2D, L2U, L3D, L3U, and L4. The lighting of lantern L1U indicates that the car is approaching the 1st floor and is prepared to start from that floor in the up direction, while lantern L1D indicates that the car is approaching the 1st floor and is prepared to start from that floor in the down direction.

100 The up-floor lanterns L1U, L2U, L3U and L4 are connected, respectively, to individual segments on floor selector FS constituting a group of segments designated by the reference character LU, to be engaged successively by a contact brush 186 carried by movable arm A as the car C approaches the corresponding floor.

105 In like manner, down-floor lanterns LB, L1D, L2D, and L3D are connected to individual segments on floor selector FS constituting a group of segments designated by the reference character LD, to be engaged by a contact brush 187 as the car approaches the corresponding floors when travelling in the down direction.

110 Car-call stopping relay 10 and floor-call stopping relay 9 are each provided with normally-open contact members *a* in circuit with brushes 130 186 and 187 for supplying current to these brushes whenever either of these relays is energized to cause the car to stop at any floor.

115 If the car is to stop in response to a floor call at the 2nd floor, when travelling upwardly, lantern L2U will be lighted as soon as floor-call stopping relay 9 is energized to cause the car to stop at that floor. The circuit for lantern L2U extends from line conductor L1, through conductors 97, 98, 188 and 189, contact members *a* of 120 186, brush 186, segment 192 in group LU, conductor 191, brush 186, segment 192 in group LU, conductor 193, lantern L2U, conductor 194, bypass switch P, conductor 80, contact member 81 on load switch LS and conductor 82, to line conductor L2.

125 When the car is brought to a stop at the 2nd floor, and relay 9 is deenergized (since brush 19 will have moved off segment 73 in group FCU as previously described for the 2nd floor stop), 130

the lantern will be extinguished unless prevention means are provided. In order to prevent extinguishing the lantern L2U until the car leaves the 2nd floor, I have provided normally-closed 5 contact members *a* on transfer relay 8, which are arranged, in any suitable manner, to be closed quickly upon the reduction of voltage output of the generator G when the car is brought to a stop. In other words, contact members *a* are not 10 affected by the time delay occasioned by dashpot 89. When contact members *a* on relay 8 are closed, a shunt circuit around contact members *a* on floor-call stopping relay 9 is completed to maintain current in the circuit for lantern 15 L2D during the entire time the car remains at the 2nd floor.

It will be observed, from an inspection of the floor selector FS, that segment 192 in group LJU extends slightly beyond the dotted line representing the position of the car at the 2nd floor level, hence, during the entire time the car is at the 2nd floor, brush 186 will be in a position to complete the circuit for L2U through segment 192.

25 The down lanterns are operated in a similar manner by engagement of brush 187 with the contact segments constituting group LD. Also, the energization of car-call stopping relay 10 will energize the floor lantern corresponding to the 30 direction of travel of the car and to the floor approached by the car, since contact members *a* on relay 10 are also arranged in the circuit for brushes 186 and 187 in the same manner as are contact members *a* on floor-call stopping relay 9.

However, when the car C approaches the 1st floor with no call existent to carry it to the basement floor, it is desirable that lantern L1U shall be lighted to indicate that the car is ready to 40 proceed on an upward trip when it leaves the 1st floor instead of lighting lantern L1D to give a false indication that the car is to travel downwardly from that floor. For this reason, I have indicated that the conductor for connecting segments 45 196 to lantern L1D passes through normally-open contact members *c* on basement call relay BC, hence, unless basement call relay BC is energized to carry the car to the basement, floor lantern L1D will not be lighted, even 50 though the car stops at the 1st floor on its way down.

In addition, I have illustrated a branch circuit for energizing lantern L1U when the car approaches the 1st floor in the down direction if 55 no call exists for service at the basement floor. This circuit extends from conductor 197 (connecting segment 198 on the up side of the floor selector FS to the lantern L1U), by way of conductor 199, normally-closed contact members *d* 60 on basement call relay BC and conductors 203 and 201, to segment 196 on the down side of the floor selector FS. It will be remembered that segment 196 is the segment normally used for lighting lantern L1D, hence, when brush 187 65 engages segment 196, lantern L1U will be lighted instead of lantern L1D, unless basement call relay BC is energized, at which time, the connections will be reversed to light lantern L1D instead of lantern L1U. In this manner, I avoid 70 the confusion resulting from a false indication being given by the floor lantern associated with car C.

In like manner, the lanterns LD', L1D', L1U', L2D', L2U', L3D', L3U' and L4' will be actuated 75 by the approach of car C' to the corresponding

floors if a stop is to be made by car C' at those floors.

It will be understood from the foregoing disclosure that I have provided an elevator system which may include as many cars in a bank as is desirable, and which, through the simple manipulation of switches at a dispatching station, may be converted from a multi-car system in which the cars will operate in all respects identical with that of a bank of cars controlled by an individual attendant on each car; which may be operated as a two-car bank with the remainder of the cars out of service when traffic conditions warrant; or which may be operated as a single-car system with the remainder of the cars out of service, without the necessity, in any case, of having an attendant on any car.

It will be understood that the embodiment of my system shown and described is illustrative only, and that I do not desire to be limited to any of the details shown herein, except as defined in the appended claims.

I claim as my invention:

1. In a control system for a plurality of elevator cars operable past a plurality of floors between two terminals, means individual to each of said cars for starting said car in either direction, call means for said floors operable to stop any of said cars at corresponding floors, means operable by the initial starting of said car in either direction for biasing said car to continue to travel after each stop in the corresponding direction to the corresponding terminal, and means selectively operable to cause consecutive actuation of the car starting means for all of said cars at regular intervals of time, to cause actuation of the starting means for one car by the initial starting of another car or to cause the starting means for one car only to be actuated upon actuation of any of said call means.

2. In a control system for two elevator cars operable past a plurality of floors between two terminals, call means for said floors for calling said cars and for stopping them upon arrival at the corresponding floors, starting means for each of said two cars, both operable upon actuation of any of said call means, means operable upon starting of either car to cause said car to move to the terminal in the direction in which it starts and means for preventing the starting of either car from a terminal until the other car arrives at the other terminal.

3. In a control system for a plurality of elevator cars operable past a plurality of floors, call means at each floor for calling said cars to said floor and for stopping the first of said cars to arrive at said floors, means operable upon starting of one car for starting the other of said cars and means for preventing the starting of either of said cars from a terminal floor until both are at terminal floors.

4. In a control system for an elevator car operable past a plurality of floors between two terminals, call means for said floors for calling said car to said floors and for stopping said car upon arrival at the corresponding floor, starting means for said car, means operable upon actuation of any of said calling means for actuating said starting means and means, operable in response to the presence of a predetermined load in said car, for actuating said starting means independent of any of said call means.

5. In a control system for an elevator car operable past a plurality of floors between two terminals, call means for said floors for calling

- said car to said floors and for stopping said car upon arrival at the corresponding floor, starting means for said car, means, operable by actuation of any of said call means, for operating said starting means, timed means for operating said starting means, and change-over mechanism operable to determine which of said last two mentioned means is to control said starting means.
6. In a control system for an elevator car operable past a plurality of floors, means for each of said floors for registering calls for service at the corresponding floors, means for normally limiting the extent of travel of said car to a zone between certain of said floors independent of the actuation of the corresponding call means and means responsive to the actuation of a call means for a floor outside said zone for rendering said limiting means ineffective.
7. In a control system for a plurality of elevator cars, means for operating each of said cars including starting mechanism, and switching mechanism responsive to the position of one of said cars for controlling the starting mechanism for the other of said cars.
8. In a control system for a plurality of elevator cars operable between two terminal landings, means to control the starting of one of said cars from a terminal landing comprising starting connections for that car, and means comprising switching means responsive to the approach of the other of said cars to the other terminal landing for controlling said starting connections.
9. In a control system for a plurality of elevator cars operable between upper and lower terminal positions, starting mechanism for each of said cars, and means adapted to prevent actuation of the starting mechanism for either of said cars to cause that car to leave a terminal position until after the arrival of the other of said cars at the other terminal position.
10. In a control system for a plurality of elevator cars, starting means for each of said cars, and means adapted to respond to the actuation of the starting means for either car for causing actuation of the starting means for the other car.
11. In a control system for a plurality of elevator cars operable between two terminal landings, starting means for each of said cars, and means adapted to respond to the actuation of the starting means for either car to cause that car to leave one terminal landing, and, in the event said cars are standing at opposite terminals, to cause actuation of the starting means for the other car to cause that car to leave said other terminal landing.
12. In a control system for a plurality of elevators cars operable past a plurality of floors, up and down starting means for each of said cars, call-registering means for each of said floors, and means adapted to respond to operation of any one of said call-registering means to cause actuation of the up-starting means for one of said cars and of the down starting means for another of said cars.
13. In a control system for a plurality of elevator cars operable in hatchways past a plurality of landings intermediate upper and lower terminal positions, up and down mechanism for each of said cars, call-registering means associated with each of said landings, and means adapted to respond to operation of any of said call-registering means, if said cars are standing at opposite terminal positions, to cause actuation of the up-starting mechanism for one of said cars and to cause actuation of the down starting mechanism for the other of said cars.
14. In a control system for a plurality of elevator cars operable past a plurality of floor landings between two terminals, up and down starting mechanism for each of said cars, up and down call-registering means for each of said landings, and means adapted to respond to operation of either call-registering means for any floor, in the event said cars are standing at opposite terminals, to cause actuation of the up-starting mechanism for one of said cars and to cause actuation of the down starting mechanism for the other of said cars.
15. In a control system for a plurality of elevator cars operable between a plurality of landings between two terminals, means to control the initial starting of either of said cars from a terminal position in accordance with the position of the other of said cars, and means rendered effective upon initial starting of either car from a terminal position to cause that car to continue to the opposite terminal position.
16. In a control system for a plurality of elevator cars operable between a plurality of landings between two terminals, means to control the initial starting of either of said cars from a terminal position in accordance with the position of the other of said cars, means rendered effective upon initial starting of either car from a terminal position to cause that car to continue to the opposite terminal position, and call-registering means associated with each of said floors operable to cause the stopping of either of said cars at the associated floor.
17. In a control system for a plurality of elevator cars operable past a plurality of floors between two terminal floors, means to control the starting of either of said cars from a terminal floor in accordance with the position of the other of said cars, and means to effect the restarting of either of said cars from an intermediate floor regardless of the position of the other of said cars.
18. In a control system for a plurality of elevator cars operable past a plurality of floors between two terminal floors, means to control the starting of either of said cars from a terminal floor in accordance with the position of the other of said cars, means to effect the restarting of either of said cars from an intermediate floor regardless of the position of the other of said cars, and call-registering means for each intermediate floor operable to cause the stopping of either of said cars at the associated floor.
19. In a control system for an elevator operable past a zone of adjacent floors and an additional floor beyond the lower limit of said zone, means associated with up-direction travel of said car, means associated with down direction travel of said car, transfer mechanism disposed to respond to the approach of said car to the floor corresponding to the lower limit of said zone to render said down-direction means ineffective and to render said up-direction means effective, and means to render said transfer mechanism ineffective, said last-named means comprising call-registering means associated with said additional floor.
20. In a control system for an elevator car operable past a zone of adjacent floors and an additional floor below the lower limit of said zone, control means for said car comprising up-direction and down-direction mechanism, trans-

- fer means disposed to respond to the approach of said car to said lower limit of said zone to render said down-direction mechanism ineffective and to render said up-direction mechanism effective, call-registering means associated with said additional floor, and means adapted to respond to operation of said call-registering means to render said up-direction mechanism ineffective and render said down-direction mechanism effective.
21. In a control system for a plurality of elevator cars operable past a plurality of floors, passenger-operated call means for moving said cars to, and stopping them at, said floors, and means, operably responsive to the operation of one of said call means to move one of said cars in one direction to a floor, for moving another of said cars in the opposite direction.
22. In a control system for a plurality of elevator cars operable past a plurality of floors between two terminal floors, passenger-operated call means for moving said cars to, and stopping them at, said floors, and means, operably responsive to the operation of one of said call means to move one of said cars, for causing said cars to move to, and to park at, opposite terminals.
23. In a control system for a pair of elevator cars operable past a plurality of floors between two terminals, up-direction and down-direction means for registering calls to move said cars to, and to stop them at, said floors and means, operably responsive to the registration of a call in one direction for one car, for establishing a call in the opposite direction for the other car.
24. In a control system for an elevator car operable past a zone of adjacent floors and an additional floor beyond one limit of said zone, means associated with travel of said car through said zone in one direction, means associated with travel of said car through said zone in the reverse direction, circuits and contact members associated with said directional means, transfer means disposed to respond to the arrival of said car at said limit to open contact members in the circuit for one of said directional means and to close contact members in the circuit for the other of said directional means, and means comprising call-registering means associated with said additional floor for rendering said transfer means ineffective.
